Patented Oct. 9, 1917.

UNITED STATES PATENT OFFICE.

GEORGE H. HENDERSON, OF DAYTON, TEXAS.

FOLDING TABLE.

1,242,347.

Specification of Letters Patent.

Patented Oct. 9, 1917.

Application filed July 25, 1916. Serial No. 111,143.

To all whom it may concern:

Be it known that I, GEORGE H. HENDERSON, a citizen of the United States, residing at Dayton, in the county of Liberty and 5 State of Texas, have invented certain new and useful Improvements in Folding Tables, of which the following is a specification.

This invention relates to new and useful improvements in a folding table. The object of the invention is to provide a table of the character described, so constructed that its parts may be readily folded together and the table collapsed so as to occupy small space.

15 With the above and other objects in view the invention has particular relation to certain novel features of construction, arrangement of parts and use, an example of which is given in this specification and illustrated 20 in the accompanying drawings wherein:—

Figure 1 is a plan view of the table with the leaves removed.

Fig. 2 is an end view showing the table in collapsed condition.

25 Fig. 3 is a side view showing the table in collapsed position.

Fig. 4 is a sectional view thereof taken on the line 4—4 of Fig. 1 and,

30 Fig. 5 is a sectional view thereof taken on the line 5—5 of Fig. 1.

Referring now more particularly to the drawings, the numeral 1 designates an oblong bridge whose respective ends are supported by the legs 2 and 3. This bridge is 35 offset at its center on each side forming the shoulders 4, 4, the offset position of the bridge being about one-third of the width of the other position. Hinged to the outer angle of the respective shoulders 4, 4, are 40 the corresponding arms 5, 5, whose free ends are supported by the respective legs 6, 6, which are hinged thereto, so as to be readily folded up against the under sides of the corresponding arms 5, 5.

The table is provided with two semi-circular leaves 7, 7, whose straight edges meet along the central line of the bridge when the table is in use and which are hinged to the respective edges of the wide part of the bridge. When the table is in use, the leaves 45 are extended to a horizontal position and the arms 5, 5, swung around at right angles of the bridge, the free ends of said arms when in this position being supported by the legs 6, 6, and the arms supporting the leaves 50 of the table. When it is desired to fold up or collapse the table, the arms, 5, 5, are swung around into alignment with the bridge, the outer sides of said arms being 55 flush with the outer edge of the wide part 60 of the bridge, thus permitting the respective leaves to fall down into a vertical position as shown in Fig. 2 and the legs 6, 6 are then folded up against the undersides of the corresponding arms 5, 5, said legs being held 65 in said position by means of catches 8 and the table will thus be in a compact position so as to take small space when not in use.

What I claim is:

A table of the character described including an oblong bridge, offset at its center on each side forming shoulders, arms hinged to the outer angles of the respective shoulders, supporting legs fixed to the respective ends of the bridge and to the free ends of said arms, two leaves whose adjacent edges meet along the central line of the bridge; said leaves being hinged to the corresponding edges of the bridge and being supported by the arms when said arms are swung into 75 angular position relative to the bridge. 80

In testimony whereof I have signed my name to this specification in the presence of two subscribing witnesses.

GEORGE H. HENDERSON.

Witnesses:

FLORENCE JOHNSTON,
RUBY GLAZNER.
